RAPPING PLATE

Thomas Lee Ruddy, Lakewood, Ohio

Application March 26, 1946, Serial No. 657,290

1 Claim. (Cl. 22—186)

1

This invention relates to rapping plates for attachment to molding patterns and the like, and has for one of its objects the provision of a device of this kind that may be so substantially and firmly secured to the pattern that it will withstand the severe service to which it is ordinarily subjected.

A further object of the invention is to provide a very simple device of this kind which will be inexpensive to manufacture, light in weight and durable.

Another object is to provide a rapping plate which has an increased surface area to bear against the pattern to which it will be applied and yet which will be light in weight and easy to apply.

A more specific object is to provide a rapping plate capable of distributing a force applied to it from any direction over a greater area of the pattern, thereby reducing the possibility of deformation of the pattern and the ultimate loosening of the plate.

Another specific object is to provide a new and novel rapping plate so strengthened that warpage resulting from long use will be reduced.

A further specific object is to provide a rapping plate having a new and novel means of preventing loosened hold-down screws from interfering with the making of perfect patterns.

Other objects of the invention and the features of the novelty will be apparent from the following description taken in connection with the accompanying drawing, wherein like characters indicate like parts, of which

Fig. 1 is a top view illustrating my improved rapping plate.

Fig. 2 is a longitudinal section through the rapping plate on the sectional line 2—2 shown as though mounted on a pattern, and

Fig. 3 is a bottom view of my improved rapping plate showing in detail the depending lugs and webbing of the plate designed to engage the pattern.

Referring to the drawing, 1 indicates generally a pattern such as is commonly made of wood or other material, and 2 indicates the rapping plate which is attached to the pattern by means of the screws 3.

The rapping plate may be made in various sizes and shapes to suit different patterns but as illustrated consists of a substantially hexagonal shaped plate 4 having sides substantially perpendicular to the plane of the plate. Depending from the plate 4 and with their outer surfaces flush with the outer surface of the sides are a plurality of depending lugs 5, 6, 7 and 8. The outer surface

2

of these lugs, as well as the sides of the plate, are substantially perpendicular to the plane of the plate 4. The other surfaces of these lugs including longitudinal edges 9, 10 have all been provided with a slight taper. In use, the full surface of these lugs is in engagement with the pattern and any blows delivered to the rapping plate will be distributed to the pattern throughout this area of contact. The taper permits a slight wedging action when the lugs are driven into the holes provided for them so as to increase the firmness of their bearing on the pattern material.

Also depending from the lower surface of the plate 4 and preferably on the centerline is a boss 11, preferably made hollow as at 12 in order to keep the weight of the rapping plate as low as possible. The outer surface of this boss is also designed to be in firm engagement with the pattern material and aids in transmitting the force of the blows to the pattern material.

Extending from the boss 11 outwardly are ribs 13. These ribs not only serve to give added strength to the boss but also serve to further increase the area of the surfaces in contact with the pattern capable of transmitting the force of the blows to the pattern material. In addition these ribs considerably increase the bending movement of the plate so as to reduce to a minimum warpage from excessive use. Preferably these ribs extend 30 in a direction such that their surfaces will be at an angle with the major surfaces of the depending lugs 5, 6, 7 and 8. This serves to increase the number of surfaces which will have a plane perpendicular to the direction of any blow delivered to the plate.

Holes 17 and 18, having a slight taper, are designed to receive a rapping or withdrawal bar. They are placed outwardly of the center of the rapping plate in order that blows thereon will tend to give a slight turning movement to the plate, which in turn is transmitted to the pattern so as to aid in the pattern's removal.

Recesses 20 are provided in the surface of the plate around each hold-down screw hole to permit the screwhead of the hold-down screw to be countersunk well below the surface of the plate. Thus a loosened screw will not interfere with the matching of the opposite halves of the pattern. Malleable lugs 19 are provided in the recesses 20 which can be bent over the head of the screws 3 to prevent removal or loosening of the screws.

The location and the design of the lugs 5, 6, 7 and 8 is such as to make the operation of applying the rapping plate to a pattern and locating the holes for the lugs a simple matter. The plate

is laid bottom side up on the pattern and the outline of the plate traced thereon with a pencil. As the outer surfaces of the lugs are flush with the sides of the plate, this outline also indicates where the holes should be made for the lugs. A 5 drill or other woodworking tool following the outline traced on the pattern is then used to make the holes for the lugs. The dimensions for this hole should be approximately the same as the smaller end of the lug so that when the lug is 10 later driven into place, a firm fit will result. The center of the hole for the depending boss 11 may be easily located by means of the intersection of diagonal lines drawn from the corners of the 15 outline and a drill used to make this hole. Then by means of a routing tool the remainder of the pattern is cut away to a depth equal to that of the plate 4. The plate is then placed in this opening and hammered into place. The hammer 20 blows are sufficient that the webs 13 will deform the pattern material and make their own space. If not, a space may be cut for them. The screws 3 are then applied and the malleable lugs 19 hammered over to prevent the screws from coming out.

Thus it is seen that I have described a rapping plate simple in construction and easily applied which will have a firm engagement with the pattern over a much larger area than has heretofore been known in devices of this kind, which will prevent warpage and which will prevent loosened screws from interfering with the making of perfect patterns.

While I have illustrated and described what I now consider to be the preferred form of my invention, it will be understood that changes in the shape and arrangement of the parts may be made without departing from the spirit of the invention as defined in the appended claim.

Having thus described my invention, I claim:

A rapping plate for patterns or the like comprising a plate member, a plurality of spaced lugs integral with said member and extending outwardly from one face of the latter with the outer surface of each lug substantially perpendicular to the plane of the member and flush with a portion of the periphery thereof, the inner surfaces of said lugs being substantially planar and tapering towards said outer surfaces, a hollow boss extending outwardly from a central imperforate portion of said one face of the member, a plurality of webs radiating from said boss and integrally united with the latter and with the said one face of the member, the other face of said member being provided with a plurality of depressions of substantial dimensions with a screw-receiving opening through the member disposed substantially centrally of each depression, and a plurality of lugs in each depression adjacent the opening therein, the last-mentioned lugs being integral with said member and adapted to be bent over the heads of screws in said openings and depressions to prevent the screws from being displaced outwardly thereof.
